UNITED STATES PATENT OFFICE.

GEORGE E. GREENLEAF AND CLIFFORD F. RANDOLPH, OF PLAINFIELD, NEW JERSEY,
ASSIGNORS TO NILES-BEMENT-POND COMPANY, OF NEW YORK, N. Y., A CORPO-
RATION OF NEW JERSEY.

LATHE HEADSTOCK.

1,422,098.

Specification of Letters Patent.

Patented July 11, 1922.

Application filed November 9, 1918. Serial No. 261,780.

To all whom it may concern:

Be it known that we, GEORGE E. GREENLEAF and CLIFFORD F. RANDOLPH, citizens of the United States, residing at Plainfield, in the county of Union and State of New Jersey, have invented certain new and useful Improvements in Lathe Headstocks, of which the following is a specification.

The invention relates particularly to improved gearing for lathe headstocks. One of the objects of the invention is to provide gearing which is simple in construction, which has many advantages in operation and maintenance, and which can be manufactured at less expense than other gearing which has been used or proposed for the same purpose. A further object of the invention is to provide an improved mechanism for adjusting the gearing to secure different spindle speeds. Still another object of the invention is to provide an improved general arrangement of the parts whereby the main drive gearing for the spindle is enclosed in an oil-tight casing and whereby the secondary gearing, particularly the feed gearing, is exposed so that it can be readily adjusted or changed. Another object of the invention is to provide improved means for turning the gearing or parts thereof to permit sliding engagement. Further objects of the invention will be apparent from the following specification and claims.

In the accompanying drawings we have illustrated the embodiment of the invention which we now deem preferable, but it will be understood that the drawings are for illustrative purposes only and are not intended to define or limit the scope of the invention, the accompanying claims being relied upon for that purpose.

Of the drawings:

Fig. 1 is a front view, partly in section and partly in elevation, of a lathe headstock embodying the invention.

Fig. 2 is an outer end view.

Fig. 3 is an inner end view with the face plate removed and with the spindle shown in section.

Fig. 4 is a plan view of the lower part of the frame and of the gearing parts directly carried thereby.

Fig. 5 is a fragmentary plan view partly in section along the line 5—5 of Fig. 1.

Figs. 6 and 7 are fragmentary detail views

showing a part of the gear shifting mechanism in two different positions.

Fig. 8 is a fragmentary detail view of another part of the gear shifting mechanism.

Referring to the drawings, 1 represents the bed of the lathe. Mounted upon this bed in the usual manner is a lathe headstock which comprises a frame having lower and upper sections 2 and 3 respectively. The headstock frame is preferably constructed in the form of a casing or housing having imperforate external walls which enclose the major portions of the gearing and other moving parts.

The main spindle of the lathe is indicated at 4 and this is mounted in bearings 5 and 6 at the inner and outer ends respectively of the lower section 2 of the frame. Preferably the bearings 5 and 6 are provided respectively with caps 5^a and 6^a which extend above the lower section of the frame into recesses formed in the walls of the upper section. A drive shaft 7 and two countershafts 8 and 9 are mounted in the headstock frame. These shafts are all parallel with the spindle and each of them is mounted in bearings which hold its axis in fixed position. The arrangement of these shafts may vary somewhat but we prefer the arrangement which is illustrated. The drive shaft 7 is mounted in the upper section of the frame, there being two bearings 10 and 11 located inside the frame and a bearing 12 located at the outer end of the frame. The shaft 7 preferably projects out through the end of the bearing 12 for a purpose to be presently set forth. The first countershaft 8 is mounted in the lower section of the frame, there being one bearing 13 located at the inner end of the frame, a bearing 13^a inside of the frame and a bearing 14 at the outer end of the frame. The second countershaft 9 is also mounted in the lower section of the frame, there being one bearing 15 inside of the frame and a bearing 16 at the inner end thereof.

100 The drive shaft 7 can be rotated in any usual or preferred way. For purposes of illustration we have shown an electric motor 17 which is mounted on the top of the upper section of the frame. From the motor power is transmitted through a train of 105 gearing 18 to a gear 19 on the shaft 7. The gearing 18 is supported in an auxiliary

frame 20 which is preferably in the form of a casing or housing which encloses the gearing.

Interposed between the drive shaft 7 and the first countershaft 8 is a multiple-speed change-gear connection preferably of the sliding-gear type as shown in the drawing. This connection can be varied as concerns the number of speeds provided and as concerns the various detail's. When the connection is constructed in the preferred way we provide for two speeds. Rigidly secured to the shaft 7 are two differently diametered gears 21 and 22. Slidably mounted on the countershaft 8 are two differently diametered gears 23 and 24 adapted to mesh respectively with the gears 21 and 22. The gears 23 and 24 are movable in unison and can be positioned either with the gears 21 and 23 in mesh, as illustrated, or with the gears 22 and 24 in mesh. It will be seen that the shaft 8 can be driven at either of two speeds in accordance with which set of gears is in mesh.

Mounted respectively on the first countershaft 8 and on the spindle 4 are two gears 25 and 26 adapted to mesh with each other. One of these gears is longitudinally slidable so that it can be moved into or out of mesh with the other gear. Preferably the gear 25 on the countershaft is the one which is slidably mounted, the gear 26 on the spindle being rigidly secured thereto. When the gear 25 is in mesh with the gear 26 power is transmitted from the drive shaft 7 through the countershaft 8 to rotate the spindle at either of two speeds, depending on the adjustment of the sliding gear connection. With the gear 25 out of mesh with the gear 26, as illustrated, the shaft 8 is free to rotate without driving the spindle by means of the gear 26.

Mounted respectively on the first and second countershafts 8 and 9 are two gears 27 and 28 which are adapted to mesh with each other. Preferably one of the gears is longitudinally slidable into or out of mesh with the other, this preferably being the gear 28 on the shaft 9. Carried by the spindle 4 at its front end is a face plate 29 which can be of any usual or preferred construction. Secured to or formed as a part of this face plate is a large drive gear 30 which is preferably an internal annular gear. At the front end of the second countershaft 9 is a pinion 31 which is adapted to mesh with the gear 30 but which is longitudinally movable into or out of mesh therewith. By preference the pinion 31 is rigidly secured to or formed as a part of the countershaft 9 and the entire countershaft is movable longitudinally to bring the pinion 31 into or out of mesh with the gear 30. Preferably the gear 28 is also rigidly secured to the countershaft 9 so that it and the pinion 31 are simul-

taneously engaged with or disengaged from the gears 27 and 30 respectively. As illustrated, the pinion 31 is formed integrally with the shaft 9, the diameter of the shaft at the bearing 16 being the same as or larger than the diameter of the gear. This permits the pinion to move backward into the bearing when disengaged from the gear 30. When the gears 27 and 28 are in mesh and when the pinion 31 and the gear 30 are also in mesh, power is transmitted from the drive shaft 7 to the countershaft 8 in the way before described and from the countershaft 8 power is transmitted to the countershaft 9 and thence to the spindle by means of the face plate gear 30. When the countershaft 9 and the face plate gear 30 are in use the speed ratio between the spindle and the gear 8 is much less than when the gear 26 is in use. Inasmuch as the countershaft 8 can be rotated at two speeds, as before described, it will be obvious that by adjusting the gearing the spindle can be driven from the drive shaft 7 at any one of four speeds. Preferably the motor 17 is of the variable-speed type and by means of the motor additional variations in speed can be secured.

It is obvious that the gears 25 and 26 and the gears 31 and 30 should not be engaged at the same time, and we therefore provide interlocking means for preventing such simultaneous engagement. The interlocking means preferably constitutes a part of the mechanism which is also used for shifting the gears. As illustrated, the gear 25 is provided with a grooved collar 32 which is engaged by an arm 33 on a longitudinally slid- 95 able rod 34. The countershaft 9 is provided at 35 with a groove which is entered by an arm 36 on a longitudinally slid- 100 able rod 37. As illustrated, the rod 34 is vertically above the rod 37 and a short transverse horizontal operating shaft 38 is positioned between them. This shaft 38 is rotatably supported in the main frame and is provided at its 110 front end with a hand lever 39 by means of which it may be moved. Secured to the shaft 38 is a disk 40 having spur gear teeth 41 along a part of its circumference. These teeth 41 are adapted to mesh either with 115 teeth 42 on the rod 37 or with teeth 43 on the rod 34. The disk 40 is also provided with a cylindrical surface 44 with a radius less than that of the teeth at the outside. The rod 34 is provided with a curved recess 120 45 adapted to receive the cylindrical part 44 of the disk, and the rod 37 is provided with a similar recess 46 adapted to receive the said part 44. As illustrated in Fig. 6, the gear teeth 41 are in mesh with the gear teeth 125 42 and the cylindrical part 44 of the disk is seated in the recess 45 of the rod 34. It will be seen that with the parts in this position the rod 34 is locked against longitudinal movement, thus holding the gear 25 130

against longitudinal movement. The rod 37 is in position to hold the pinion 31 in mesh with the gear 30. It will be seen, however, that by turning the lever 39 in the clockwise direction, the rod 37 can be moved toward the left to withdraw the pinion 31 from the gear 30. Continued movement of the lever 39 and of the disk 49 in the clockwise direction will cause the part 44 of the disk to enter the recess 46 in the rod 37, as illustrated in Fig. 7. This locks the rod 37 against further movement in either direction, thus holding the pinion 31 out of mesh with the gear 30. At the same time the teeth 41 will come into engagement with the teeth 43 of the rod 34, thus moving the rod toward the right and sliding the gear 25 into mesh with the gear 26. When the lever 39 is moved in the counter-clockwise direction 20 the above described series of steps is reversed. Means are provided whereby the lever 39 can be held either in the right-hand position shown or in the opposite left-hand position.

25 Suitable mechanism is provided for sliding the gears 23 and 24, and preferably this is associated with the mechanism described above for sliding the other gears. Connected with the gears 23 and 24 is an annularly grooved collar 47 in which fits an arm 48 on a longitudinally movable rod 49. This rod is provided with gear teeth 50 which mesh with similar teeth formed on a gear segment 51. The gear segment is secured 30 to a sleeve 52 which surrounds the above mentioned shaft 38. At the front end of the sleeve is a lever 53 by means of which the sleeve and the gear segment may be turned, thereby sliding the rod 49 and the gears 23 and 24. By moving the lever 53 in one direction or the other, either set of gears can be brought into operation. Means are provided whereby the lever can be secured in either of its extreme operative positions. 40 It will be seen that the two gear shifting levers 39 and 53 are rotatable about a common axis, thus adding to the simplicity and convenience of the machine.

Lathe headstocks as heretofore constructed 50 have commonly included a countershaft, with "back gearing" thereon, mounted for bodily movement transversely of the headstock. Usually this transverse movement has been made possible by mounting the 55 shaft in eccentric bearings which were capable of being turned. For one position of the countershaft the back gears would mesh with other gears and for the other position the back gears would be out of mesh. It has also been common in lathes of this type 60 to construct one of the power transmitting shafts in the form of a sleeve or bushing surrounding the spindle and independently rotatable thereon. By our present construction we avoid the difficulties and much of the 65 expense associated with these two features of construction. All of the shafts and gears are mounted for rotation about fixed axes, thus avoiding the complexity of movable bearings, and each shaft is positioned for 70 rotation about its own axis, thus making it possible to provide each of them with simple independent bearings. In case of necessary repair or inspection, any shaft can be removed without removing any other shaft 75 from its bearings. It will be noted that the drive shaft is mounted in the upper section of the frame and that the entire upper section, together with the drive shaft and the gears thereon, can be removed simply by 80 loosening the bolts which connect the upper section to the lower section. The spindle can then be removed by taking off the bearing caps 5^a and 6^a. The countershafts 8 and 9 can be removed through the bearing openings at the front end of the frame.

It will be further observed that we attain the maximum of simplicity by providing 85 sliding gear connections for effecting changes in the speed ratio and that we entirely eliminate separate clutches such as have heretofore been used for this purpose in headstock drives. In earlier constructions use has been made of separate bars thrust into apertures in the gear hubs for the purpose of shifting 90 them longitudinally. In our construction, we provide gear shifting levers which are permanent parts of the headstock, and these levers are so arranged as to enable the gears to be shifted conveniently and without delay. 95

As stated above, the headstock frame is 100 preferably in the form of a casing or housing which surrounds most of the gearing and other moving parts. It will be seen that there are no exposed apertures in the 105 ends of the casing except those at the bearings and these apertures are closed by the respective shafts. At the front of the casing the only aperture is that for the sleeve 52 and shaft 38, this aperture being of course 110 closed by the said parts. It is therefore impossible for dirt and dust to have access to the operative parts of the machine and the oil which is used for lubrication is confined 115 within the casing, thus preventing waste and eliminating oily accumulations on the exterior of the machine. We provide means for circulating the oil which is used for lubrication, this oil being withdrawn from the bottom of the casing and delivered to an oil 120 reservoir 54 preferably located in the auxiliary frame 20. From the reservoir 54 the oil is distributed in any usual or preferred way, but by preference we use a lubricating system such as set forth in the patent granted 125 to George E. Greenleaf for lubricating system for lathe headstocks, 1,342,904, dated June 8, 1920. For supplying oil to the reservoir 54 we provide a power actuated pump, and in order that this pump may be readily 130

1
accessible for inspection and adjustment we locate it on the outside of the main frame casing. As illustrated, particularly in Fig. 2, the pump is represented by 55 and is of 5 the plunger type, being operated by a connecting rod 56 and an eccentric 57 near the outer end of the shaft 7. The inlet to the pump is through a pipe 58 which leads from the bottom of the casing, and the outlet is 10 through a pipe 59 which discharges into the reservoir 54.

It frequently happens that difficulty is experienced in effecting the engagement of one gear with another due to the fact that the 15 teeth are exactly in alinement. In order to facilitate the engagement of the gears under such circumstances, we preferably provide means whereby one of the gears may be turned manually through a small angle. The 20 means which we prefer for this purpose is associated with the drive shaft 7. As illustrated, the drive shaft is provided at its end with a bevel gear 60. Mounted in a suitable bearing bracket 61 on the upper section of 25 the main frame is a transverse horizontal shaft 62 which is slidable endwise. This shaft carries at its rear end a bevel gear 63 which is adapted to mesh with the bevel gear 60. At the front end of the shaft 62 is a 30 smooth hand wheel 64 by means of which the shaft may be turned. It will be seen that when the bevel gears 63 and 60 are engaged the operator, by turning the hand wheel 64 can turn the shaft 7 and thus turn all of the 35 gears that are mounted on or connected with the said shaft. Obviously it is necessary to turn the gears only through a very small angle to enable meshing to take place.

In order that the shaft 62 and the hand 40 wheel 64 may not rotate continuously when the lathe is in operation we provide a spring 65 which surrounds the shaft 62 and tends to move it forward, thus disengaging the bevel gear 63 from the bevel gear 60. Preferably also the end of the bracket 61 is beveled and the shaft 62 is provided with a pin 45 66 adapted to mesh with the beveled or cam-like surface. When the pin 66 is opposite the low part of the cam the operator can 50 move the shaft 62 rearward against the resistance of the spring, thus engaging the bevel gears. Then by turning the hand wheel 64 he can move the gearing as may be necessary. It should be noted that it is necessary to turn the gears only through a very 55 small angle to enable the desired meshing of the sliding gears to take place and therefore in operation, the pin 66 will need to pass over only a very small portion of the lower 60 part of the cam to perform its function. When the hand wheel is released the spring 65 operates to separate the bevel gear 63 from the bevel gear 60. The cam surface at 65 the end of the bearing and the pin 61 serve as a safety means to insure the movement of

the shaft and bevel gear forward in case of failure of the spring. If the shaft 7 is in rotation or starts to rotate while the bevel gears are engaged, the resultant turning of the shaft 62 will cause the pin 66 to ride up 70 on the cam surface, thus positively forcing the shaft outward and disengaging the bevel gear 63.

The main gearing for driving the spindle is for the most part enclosed in the main frame 75 casing, this arrangement serving to protect the gearing and to insure proper lubrication thereof. The feed gearing, however, must be frequently inspected and adjusted, and we therefore mount this entirely on the outside of the casing. This enables us to secure access to any part of the feed gearing without the necessity of removing any parts of the main casing and without sacrificing the advantages of a closed main casing. 80 The feed gearing is driven from the main spindle 4, there being provided for this purpose a gear 67 secured to the spindle near the outer end on the outside of the casing. We provide a thrust bearing for the spindle 90 which is also located on the outside of the casing where it is readily accessible for inspection and lubrication. This bearing consists of a bracket 68 which is secured to the lower section of the main frame by means 95 of bolts 69, 69. Interposed between the bracket 68 and the end of the spindle is a suitable thrust collar 70 together with associated parts which need not be described in detail as they of themselves constitute no 100 part of the invention. It will be observed that the bracket 68 is constructed to bridge over and partly surround the gear 67. In this way we are able to secure the advantages incident to having both the thrust 105 bearing and the initial feed gear on the outside of the casing.

The gear 67 meshes with an idler gear 71 mounted on a stud 72. The gear 71 in turn meshes with an idler gear 73 on a shaft 74. 110 Pivotally mounted on the shaft 74 is an adjustable slotted link 75. A gear 76 is also mounted on the shaft 74 and this meshes with a gear 77 on a stud 78 which is adjustably mounted in the slot of the link 75. The gear 77 meshes with a gear 79 on a drive shaft 80 of a change-speed mechanism 81. It will be seen that the speed ratio between the drive gear 67 and the shaft 80 can be changed by removing one or more of the 115 gears 76, 77 and 79 and substituting others of different diameters. The stud 78 can be moved along the link and the link as a whole can be swung to enable the differently diametered gears to properly mesh. Bolts 82, 82 120 are provided for holding the link in adjusted position.

The change-speed mechanism includes a frame or casing which is secured to the bed 1, the bed preferably being recessed, as 130

shown at 83, to receive a part of the mechanism. The change-speed mechanism 81 includes a shaft 84 parallel with the shaft 80, which is in alinement with and is directly connected to the main feed shaft or screw 85 of the lathe. Loosely mounted on the shaft 84 are two differently diametered gears 86 and 87 and mounted on the shaft 80 are two differently diametered gears 88 and 89. The gears 87 and 88 are arranged to permanently mesh with each other. Splined on the shaft 80 is a gear 90 which is adapted to mesh with the gear 86 on the shaft 84. The gear 90 carries clutch teeth adapted to mesh with similar teeth connected with the gears 88 and 89. The gear 90 can be moved by means of a lever 91 which is adapted to be operated by a hand lever 92. Splined on the shaft 84 is a gear 93 adapted to mesh with the gear 89 and having clutch teeth adapted to mesh with similar clutch teeth connected with the gears 87 and 86. The gear 93 can be moved by means of a lever 94 adapted to be operated by a hand lever 95. With the parts in the position shown, power will be transmitted from the gear 90 through the gears 86, 87, 88 and 89 to the gear 93 which rotates the shaft 84 and the feed screw 85. If the gear 90 be moved toward the right it is disengaged from the gear 86 and becomes directly connected with the gears 88 and 89. The gear 89 is thus directly driven and the speed of rotation of the shaft 84 is increased. If the gear 93 be moved toward the left it is disengaged from the gear 89 and becomes directly connected with the gears 87 and 86. With this arrangement the drive is similar to that last above referred to except that the drive is through the gears 88 and 87 instead of the gears 88 and 93. It will be seen that with the mechanism shown, any one of four speed ratios can be obtained in the gear box.

The closed casing which we have shown and described enables us to retain the oil which is used for lubricating the bearings and the gears, and further enables us to protect the gearing and other parts from dust and dirt. Notwithstanding the closed casing the several parts can be readily removed, as already stated. While securing the several advantages incident to a closed casing surrounding the main gearing, we nevertheless avoid the disadvantages which would be incident to enclosing the feed gearing. This feed gearing is placed entirely on the outside of the casing which encloses the main gearing, and it is therefore accessible for inspection and adjustment. The change-speed mechanism which drives the feed shaft constitutes a distinct unit and is readily accessible. It can be easily detached from the machine for inspection or repair without disturbing the other parts of the machine.

What we claim is:

1. In a lathe headstock, the combination of a spindle, two shafts parallel with the spindle and each rotatable about a fixed axis, a driving connection between the first shaft and spindle comprising two companion gears mounted respectively thereon, the driving connection between such gears being adapted to be disengaged, a driving connection between the two shafts comprising two companion gears mounted respectively thereon, a face plate gear carried by the spindle, and a second gear on the second shaft slidable axially into and out of mesh with the face plate gear. 70 75 80

2. In a lathe headstock, the combination of a spindle, two shafts parallel with the spindle and each rotatable about a fixed axis, two companion gears mounted respectively on the spindle and on the first shaft, 85 one of them being slidable axially into or out of mesh with the other, two companion gears mounted respectively on the two shafts, a face plate gear carried by the spindle, and a second gear carried on the 90 second shaft slidable into and out of mesh with the face plate gear.

3. In a lathe headstock, the combination of a spindle, two shafts parallel with the spindle and each rotatable about a fixed axis, 95 two companion gears mounted respectively on the spindle and on the first shaft, one of them being slidable axially into and out of mesh with the other, two companion gears mounted respectively on the two shafts, a 100 face plate gear carried by the spindle, a second gear on the second shaft adapted to mesh with the face plate gear, and means for sliding the second shaft longitudinally to bring either of the gears thereon into 105 mesh with its companion gear and to bring the other gear out of mesh with its companion gear.

4. In a lathe headstock, the combination of a spindle, two shafts parallel with the spindle and each rotatable about a fixed axis, 110 two companion gears mounted respectively on the two shafts, two companion gears mounted respectively on the spindle and on the first shaft, one of them being 115 slidable into or out of mesh with the other, a face plate gear carried by the spindle, a gear on the second shaft slidable axially into or out of mesh with the face plate gear, and interlocking means for preventing 120 simultaneous meshing of the gears of the last two said sets.

5. In a lathe headstock, the combination of a spindle, two shafts parallel with the spindle and each rotatable about a fixed axis, 125 two companion gears mounted respectively on the two shafts, two companion gears mounted respectively on the spindle and on the first shaft, one of them being slidable axially into or out of mesh with the other, 130

- 6 a face plate gear carried by the spindle, a second gear on the second shaft slidable axially into or out of mesh with the face plate gear, and gear shifting mechanism 5 including a hand lever adapted by a single continuous movement to slide a gear of the last two said sets into mesh with its companion and to slide a gear of the other set out of mesh with its companion.
- 10 6. In a lathe headstock, the combination of a spindle, a drive shaft and two countershafts parallel with the spindle and each rotatable about a fixed axis, a multiple-speed change-gear driving connection between the drive shaft and the first countershaft, a gear connection between the spindle and the first countershaft, such connection being adapted to be disconnected, a gear connection between the two countershafts, and 15 20 a gear connection between the spindle face plate and the second countershaft, said last two connections being adapted to be disconnected.
7. In a lathe headstock, the combination 25 of a spindle, a drive shaft and two countershafts parallel with the spindle and each rotatable about a fixed axis, a multiple-speed sliding-gear connection between the driving shaft and the first countershaft, two 30 companion gears mounted respectively on the spindle and on the first countershaft, one of them being slidable axially into or out of mesh with the other, two companion gears mounted respectively on the two countershafts, a face plate gear carried by the spindle, and a second gear on the second countershaft slidable axially into or out of mesh with the face plate gear. 35
8. In a lathe headstock, the combination 40 of a spindle, a drive shaft and two countershafts parallel with the spindle and each rotatable about a fixed axis, a multiple-speed gear connection between the driving shaft and the first countershaft including 45 sliding gears on the countershaft, two companion gears mounted respectively on the spindle and on the first countershaft, the gear on the countershaft being slidable axially into or out of mesh with the gear on 50 the spindle, two companion gears mounted respectively on the two countershafts, a face plate gear carried by the spindle, and a second gear on the second countershaft slidable axially into or out of mesh with the face 55 plate gear.
9. In a lathe headstock, the combination 60 of a spindle, a drive shaft and two countershafts parallel with the spindle and each rotatable about a fixed axis, a multiple-speed sliding-gear connection between the driving shaft and the first countershaft, two 65 companion gears mounted respectively on the spindle and on the first countershaft, one of them being slidable axially into or out of mesh with the other, two companion 70 gears mounted respectively on the two countershafts, one of them being slidable axially into or out of mesh with the other, a face plate gear carried by the spindle, and a second gear on the second countershaft slidable axially into or out of mesh with the face plate gear. 75
10. In a lathe headstock, the combination of a spindle, a drive shaft and two countershafts parallel with the spindle and each 80 rotatable about a fixed axis, a multiple-speed sliding-gear connection between the driving shaft and the first countershaft, two companion gears mounted respectively on the spindle and on the first countershaft, one of them being slidable axially into or out of mesh with the other, two companion gears mounted respectively on the two countershafts, a face plate gear carried by the spindle, a second gear on the second countershaft adapted to mesh with the face plate gear, and means for sliding the second countershaft longitudinally to bring either 85 of the gears thereon into mesh with its companion gear and to bring the other gear out of mesh with its companion gear. 90
11. In a lathe headstock, the combination of a spindle, a drive shaft and two countershafts parallel with the spindle and each 95 rotatable about a fixed axis, a multiple-speed sliding-gear connection between the driving shaft and the first countershaft, two companion gears mounted respectively on the two countershafts, two companion gears mounted respectively on the spindle and on the first countershaft, one of them being slidable axially into or out of mesh with the other, a face plate gear carried by the spindle, a gear on the second countershaft slidable axially into or out of mesh with the 100 face plate gear, and interlocking means for preventing simultaneous meshing of the gears to the last two said sets. 105
12. In a lathe headstock, the combination 110 of a spindle, a drive shaft and two countershafts parallel with the spindle and each rotatable about a fixed axis, a multiple-speed gear connection between the driving shaft and the first countershaft including sliding gears on the countershaft, two companion 115 gears mounted respectively on the two countershafts, two companion gears mounted respectively on the spindle and on the first countershaft, the gear on the countershaft being slidable axially into 120 or out of mesh with the gear on the spindle, a face plate gear carried by the spindle, a second gear on the second countershaft adapted to mesh with the face plate gear, means for sliding the second countershaft longitudinally to bring either of the gears thereon into mesh with its companion gear and to bring the other gear out of mesh 125 with its companion gear, and interlocking means for preventing the simultaneous mesh- 130

- ing of the gear on the first countershaft with the spindle gear and of the gear on the second countershaft with the face plate gear.
13. In a lathe headstock, the combination of a spindle, a drive shaft and two countershafts parallel with the spindle and each rotatable about a fixed axis, a multiple-speed sliding-gear connection between the driving shaft and the first countershaft, two companion gears mounted respectively on the two countershafts, two companion gears mounted respectively on the spindle and on the first countershaft, one of them being slidable axially into or out of mesh with the other, a face plate gear carried by the spindle, a second gear on the second countershaft slidable axially into or out of mesh with the face plate gear, and gear shifting mechanism including a hand lever adapted by a single continuous movement to slide a gear of either of the last two said sets into mesh with its companion and to slide a gear of the other set out of mesh with its companion.
14. In a lathe headstock, the combination of a spindle, a drive shaft and two countershafts parallel with the spindle and each rotatable about a fixed axis, a multiple-speed sliding-gear connection between the driving shaft and the first countershaft, two companion gears mounted respectively on the two countershafts, two companion gears mounted respectively on the spindle and on the first countershaft, one of them being slidable axially into or out of mesh with the other, a face plate gear carried by the spindle, a second gear on the second countershaft slidable axially into or out of mesh with the face plate gear, and shifting mechanism for all of the slidable gears including a plurality of hand levers all movable about the same axis.
15. In a lathe headstock, the combination of a spindle, a drive shaft and two countershafts parallel with the spindle and each rotatable about a fixed axis, a multiple-speed sliding-gear connection between the driving shaft and the first countershaft, two companion gears mounted respectively on the two countershafts, two companion gears mounted respectively on the spindle and on the first countershaft, one of them being slidable axially into or out of mesh with the other, a face plate gear carried by the spindle, a second gear on the second countershaft slidable axially into or out of mesh with the face plate gear, and gear shifting mechanism including two levers movable about the same axis, means operable by one lever for adjusting the multiple-speed connection and means operable by the other lever for sliding a gear of either of the last two said sets into mesh with its companion and for sliding a gear of the other set out of mesh with its companion.
16. In a lathe headstock, an improved tool feeding mechanism comprising the combination of a spindle, driving mechanism therefor, a combined frame and casing serving to retain oil and exclude dirt, feed gearing mounted at the outer end of said frame and casing entirely outside thereof, the initial element of said feed gearing being mounted on the spindle near the outer end thereof outside of the said casing, and a feed shaft adapted to be driven by the feed gearing, the said feed gearing comprising two parallel shafts each having three gears thereon, the position of one gear on each shaft of which may be suitably varied whereby four different speeds may be given to the said feed shaft.
17. In a lathe headstock, the combination of a spindle, drive mechanism for the spindle, a combined frame and casing serving to support the said spindle and drive mechanism and serving to enclose the major portions thereof to retain oil and exclude dirt, feed gearing mounted at the outer end of the said frame and casing entirely outside thereof, the initial element of the said gearing being mounted on the spindle near the outer end thereof outside of the casing, a thrust bearing for the spindle at the outer end thereof outside of the said initial element of the gearing, and means for securing the bearing to the frame.
18. In a lathe headstock, an improved tool feeding mechanism comprising the combination of a spindle, drive mechanism therefor, a combined frame and casing serving to support the said spindle and driving mechanism and serving to enclose the major portions thereof to retain oil and exclude dirt, a bed supporting the frame and having a recess at the front outer corner thereof, feed gearing mounted at the outer end of said frame and casing entirely outside thereof, the initial element of said feed gearing being mounted on the spindle near the outer end thereof outside of said casing, a feed shaft extending longitudinally of the bed at the front thereof, change speed mechanism positioned in the recess in the bed and serving to connect the feed gearing with said feed shaft, a speed-change box enclosing the said gearing, and two hand levers on the front of said box engaging said gearing whereby one of the speed gears on each shaft may be shifted longitudinally to give a plurality of different speeds to said feed shaft.
19. In a lathe headstock, an improved tool feeding mechanism comprising the combination of a spindle, drive mechanism therefor, a combined frame and casing serving to support the said spindle and drive mechanism and serving to enclose the major portions thereof to retain oil and to exclude dirt, a bed supporting the frame, feed

gearing mounted at the outer end of the said frame and casing entirely outside thereof, the initial element of said gearing being mounted on said casing, a feed shaft 5 extending longitudinally of the bed at the front thereof, and a sliding gear change speed mechanism comprising a pair of parallel shafts having a plurality of gears thereon connecting the feed gearing with 10 the feed shaft, one of said shafts being directly connected to and in alignment with said feed shaft.

20. In a lathe headstock, the combination of a spindle or shaft, a drive shaft, multiple-speed toothed change-gear power transmitting mechanism between the drive shaft and the spindle, a frame serving to support the said spindle, the drive shaft and the power transmitting mechanism, a gear on one of 25 the above mentioned shafts, a manually rotatable shaft angularly positioned relative to the said shaft, and a gear on the manually rotatable shaft adapted to mesh with the above mentioned gear whereby the said shaft may be rotated to bring the cooperating teeth of the change-gear mechanism into meshing position, the manually rotatable shaft being adapted to be moved to disengage the said gears.

30. 21. In a lathe headstock, the combination of a spindle or shaft, a drive shaft, multiple-speed toothed change-gear power transmitting mechanism between the drive shaft and the spindle, a frame serving to support the said spindle, the drive shaft and the power transmitting mechanism, a gear on one of 35 the above mentioned shafts, a manually rotatable shaft angularly positioned relative to the said shaft, a gear on the manually rotatable shaft adapted to mesh with the above mentioned gear whereby the said shaft may be rotated to bring the cooperating teeth of the change-gear mechanism into meshing position, and a spring normally serving to move the manually rotatable shaft to hold the said gears disengaged.

45. 22. In a lathe headstock, the combination of a spindle or shaft, a drive shaft, multiple-speed toothed change-gear power transmitting mechanism between the drive shaft and the spindle, a frame serving to support the said spindle, the drive shaft and the power transmitting mechanism, a gear on one of 50 the above mentioned shafts, a manually rotatable shaft angularly positioned relative to the said shaft, a gear on the manually rotatable shaft adapted to mesh with the above mentioned gear whereby the said shaft may be rotated to bring the cooperating teeth of 55 the change-gear mechanism into meshing

position, a pin carried by the manually rotatable shaft, and a cam adapted when the shaft is turned to cooperate with the pin to move the manually rotatable shaft longitudinally and thus disengage the gears.

65

23. In a lathe headstock, the combination of a spindle, a drive shaft, multiple-speed sliding-gear power transmitting mechanism between the drive shaft and the spindle, a frame serving to support the said spindle, the shaft and the power transmitting mechanism, a bevel gear on the drive shaft, a manually rotatable shaft angularly positioned relative to the drive shaft, a bevel gear on the manually rotatable shaft adapted to mesh with the gear on the drive shaft, and a spring normally serving to move the manually rotatable shaft longitudinally and thus separate the bevel gears.

70

75

24. In a lathe headstock, the combination of a spindle, a drive shaft, multiple-speed sliding-gear power transmitting mechanism between the drive shaft and the spindle, a frame serving to support the said spindle, shaft and power transmitting mechanism, a bevel gear on the drive shaft, a manually rotatable shaft angularly positioned relative to the drive shaft, a bevel gear on the manually rotatable shaft adapted to mesh with the gear on the drive shaft, a pin carried by 90 the manually rotatable shaft, and a cam adapted when the shaft is turned to cooperate with the pin to move the manually rotatable shaft longitudinally and thus separate the bevel gears.

95

25. In a lathe headstock, the combination of a spindle, a drive shaft, multiple-speed sliding-gear power transmitting mechanism between the drive shaft and the spindle, a frame serving to support the said spindle, the shaft and the power transmitting mechanism, a bevel gear on the drive shaft, a manually rotatable shaft angularly positioned relative to the drive shaft, a bevel gear on the manually rotatable shaft adapted to mesh with the gear on the drive shaft, a spring normally serving to move the manually operable shaft longitudinally, a pin carried by the manually rotatable shaft, and a cam adapted when the shaft is turned to cooperate with the pin to move the manually rotatable shaft longitudinally, the said spring and cam acting in the same direction thus insuring the separation of the bevel gears.
